CLASP CONSTRUCTION

Eugen Prestinari, Summit, N. J., assignor to The Hadley Company, Inc., Providence, R. I., a corporation of Rhode Island

Application September 27, 1937, Serial No. 165,833

16 Claims. (Cl. 24—241)

This invention relates to connecting devices and more particularly to a center catch for a bracelet or the like.

One of the objects of this invention is to provide a connecting device which is simple and inexpensive in construction, sturdy, and durable under conditions of rigorous use. Another object is to provide a connecting device which securely connects the ends of a bracelet and effectively precludes inadvertent separation thereof. Another object is to provide a device of the above nature, which may be easily operated, and which harmonizes with the appearance of the bracelet. Other objects will be in part apparent and in part pointed out hereinafter.

The invention accordingly consists in the features of construction, combinations of elements, and arrangements of parts as will be exemplified in the structure to be hereinafter described and the scope of the application of which will be indicated in the following claims.

In the drawing which illustrates one of the various possible embodiments of my invention,

Figure 1 is a perspective view of the center clasp connecting the ends of a bracelet;

Figure 2 is a perspective view of the body of my center clasp;

Figure 3 is a perspective view of the operating lever of my center clasp;

Figure 4 is a perspective view of a pawl;

Figure 5 is a perspective view of the safety catch of my center clasp;

Figure 6 is an elevation partly in section of my center clasp during one phase of its operation;

Figure 7 is an elevation partly in section of my center clasp during another phase of its operation;

Figure 8 is an elevation partly in section of my center clasp in its closed, or bracelet-end securing position; and,

Figure 9 is a section taken along the line 9—9 in Figure 8.

Similar reference characters refer to similar parts throughout the various views of the drawing.

To afford a clearer understanding of certain features of my invention, it might be pointed out here that bracelet connectors or center catches are generally so positioned on a bracelet that they may be inadvertently opened. This is particularly true of close fitting bracelets such as are worn with a wrist watch, for example. Many of these connectors are characterized by a lever of some sort which is movable between closed and open

positions to connect the bracelet ends or permit disconnection thereof. Such levers often inadvertently swing open, unknown to the wearer, and the bracelet slips off and becomes lost. Various connectors have been devised with supplemental catches whose purpose is to retain the bracelet ends after inadvertent or purposeful opening of the main catches. Many of these catches are, however, so complicated that they are easily damaged or wear to a point of ineffectiveness so that the safety catch becomes useless. Other catches of this type are difficult to operate and are so cumbersome that they detract from the appearance of the bracelet. It is another object of this invention to provide a connecting device which obviates the above difficulties in addition to various others.

Referring now to Figure 1 of the drawing, my connector is generally indicated at 15, and (as described below) a portion of it is preferably integral with a bracelet cord link or clasp generally indicated at 16 preferably of the type disclosed in my co-pending application, Serial No. 89,319, filed July 7, 1936. Clasp 16 detachably secures the ends 17 of a bracelet cord, the other ends 18 of which are secured in a link or clasp generally indicated at 19, clasp 19 being substantially similar to clasp 16 and detachably connectable to connector 15 in a manner hereinafter described.

The body portion of connector 15 is shown in Figure 2, and comprises a housing or channel generally indicated at 20 extending from clasp 16. Housing 20 is formed by side walls 21 and 22 which extend from the sides of clasp 16 and which, with a transverse top portion 23, form an opening 24. Side walls 21 and 22 preferably curve inwardly toward one another at 25 and 26 to form sides 27 and 28 of a substantially U-shaped portion, the bottom of which is formed by preferably co-planar portions 29 and 30 which extend toward one another respectively from sides 27 and 28. Portions 29 and 30 are preferably formed to provide an opening 31 at the forward ends thereof, and a smaller opening 32 along the rear portions thereof for purposes described below.

Still referring to Figure 2, the upper edges of sides 27 and 28 are provided with flanges 33 and 34 which extend toward one another and partially close the rear portion of the channel. To the left or forwardly of flanges 33 and 34, I provide notches 35 and 36 in sides 27 and 28 and forwardly of these notches are a pair of ears 37 and 38 each provided with a perforation.

Channel ears 37 and 38 are formed to pivotally support a cover member or operating lever gen-

erally indicated at 39 in Figure 3. Operating lever 39 preferably comprises a top portion 40 having depending flanges 41 and 42 formed along the longitudinal edges thereof. At one end of lever 39 I provide a finger piece 43 from which extends a detent 44 adapted to coat with edge 23a (Figure 2) of top portion 23 to hold lever 39 in its closed position, as will be described more fully below.

10 Referring again to Figure 3, the other end of lever 39 has a journal 45 formed thereon, this journal preferably being formed by folding the end of the lever back upon itself, thus providing a bore 46 extending through the journal. Journal 45 has a slot 47 formed therein, one end 47a of this slot preferably being substantially adjacent end 45a of the journal, the other end 47b (Figure 6) of slot 47 preferably being adjacent top portion 40 of the lever. Thus slot ends 47a and 20 47b form shoulders, the purpose of which is described below.

Slot 47 (Figure 3) is formed to pivotally receive a pawl generally indicated at 48 in Figure 4, this pawl preferably comprising a substantially circular bearing portion 49 and an arm 50. Bearing portion 49 of the pawl is disposed in slot 47 (Figure 3) of lever 39 and the assembled pawl and lever are then disposed between ears 37 and 38 (Figure 2) of channel 20 wherein they are held in pivotal position by a pin 51 (Figure 6) which extends through the lever, pawl and channel ears.

Pawl 48 coats with a slideable safety catch generally indicated at 52 (Figure 5) which is preferably substantially U-shaped and comprises a bottom 53 having an elongated slot 54 formed in the free end thereof. The free end 55 of bottom 53 of the catch is preferably bent downwardly with respect to the plane of bottom 53 so that end 54a of slot 54 (see Figure 6) is inclined from the horizontal. Catch 52 (Figure 5) also includes an upper portion 56, on the end of which is formed a finger piece 57 having suitable notches formed therein for engagement by the finger nail to operate the catch. The free end 57a of finger piece 57 is preferably beveled (see Figure 6) for a purpose hereinafter described. Preferably a pair of ears 65 (Figure 5) extend upwardly from lower portion 53 substantially to upper portion 56 of catch 52 to prevent undue flattening or bending of the catch from excessive pressure on finger piece 57. Preferably the width of catch portions 56 and 53 slightly exceeds the space between sides 27 and 28 (Figure 2) of channel 20. Accordingly, positioning of catch 52 between walls 27 and 28 of channel 20 causes the walls to spring apart slightly (this action being possible because of opening 32 between bottom portions 29 and 30). Thus while catch 52 is slideable in channel 20, it is frictionally held by the channel walls against inadvertent movement. Flanges 33 and 34 (Figure 2) prevent displacement of catch 52 upwardly of the channel.

Referring now to Figures 6, 7 and 8, wherein the several parts shown in Figures 2, 3, 4 and 5 are shown in assembled relationship, catch 52 lies within housing 20 and when in its open position (Figure 6) its finger piece 57 lies to the right of notches 35 and 36, leaving the notches open. When catch 52 is in this position, pawl arm 50 rests against inclined end 54a of catch slot 54 in a position to draw the catch to the left, as viewed in Figure 6, when actuated by lever 39, as will be described in greater detail.

75 Bracelet cord link or clasp 19 (Figure 1) is

provided with extended side walls 58 and 59 connected by a cross bar 64, framing an opening 60. Cross bar 64 (Figure 9) comprises top portions 61 and 62, and a depressed portion 63 which is inclined from the horizontal for a purpose hereinafter described. As shown in Figure 7, operating lever 39, when in its open position, may be threaded through the opening 60 in the end of clasp 19 so as to position depressed portion 63 of cross bar 64 against beveled edge 57a of the safety catch finger piece 57. Cross bar 64 is so positioned when safety catch 52 is in its closed position, i. e., when the catch lies in the left-hand portion of housing 20 (Figure 7), that it prevents entry of cross bar 64 into notches 35 and 36. However, operating lever 39 may be swung in a clockwise direction until its flanges 41 and 42 engage top portions 61 and 62 of cross bar 64. Further clockwise movement of operating lever 39 forces bottom portion 63 of cross bar 64 against bevel 57a on catch 52 and presses the catch to the right as viewed in Figure 7 to permit entry of the cross bar into notches 35 and 36. As cross bar portion 63 is inclined it acts like a knife edge to facilitate the opening action. Continued clockwise movement of operating lever 39 into the position shown in Figure 8 results in engagement of end 47a of lever slot 47 by pawl arm 50 so that pawl 48 is forced against slot end 54a of catch 52 to pull the catch to the left, as viewed in Figure 8, thus drawing the left-hand end of catch finger piece 57 over cross bar 64 to retain the cross bar within slots 35 and 36. When this movement of pawl 48 is completed, the end of pawl arm 50 lies within opening 31 in the bottom of channel 20 (Figure 8). Also, lever 39 has been forced to its closed position wherein detent 44 frictionally engages edge 23a of channel top portion 23, thus holding lever 39 in closed position.

When it is desired to disconnect clasp 19 from connector 15 (Figure 8), lever 39 is lifted in counter-clockwise direction by finger piece 43 and swing to the position shown in Figure 6. This movement of the lever, however, has no effect on safety catch 52 (Figure 8) because of the length of lever slot 47. Slot 47 is accordingly a lost motion device for actuating pawl 48 in a clockwise or closing direction. Hence, when lever 39 is in open position, as shown in Figure 6, safety catch 52 can only be moved from its closed position, shown in Figure 8, by independent manipulation, i. e. by way of finger piece 57.

It may now be seen that if lever 39 is inadvertently opened, safety catch 52 remains in its closed position to maintain cross bar 64 of clasp 19 connected to connector 15, and this because of the frictional engagement of safety catch 52 between walls 27 and 28 of channel 20. Furthermore, because of the lost motion caused by lever slot 47 (Figure 7), shoulder 47a of the slot does not engage pawl 48 until safety catch 52 has been forced to the right (its open position): for example when flanges 41 and 42 force cross bar 64 against bevel 57a to move the bar into notches 35 and 36. This leaves catch 52 free to close upon downward movement of lever 39, as described above.

To summarize the operation of my connector: Lever 39 is moved to its open position as shown in Figure 6, wherein it may be threaded through opening 60 of clasp 19. If safety catch 52 is in its open position, as shown in Figure 6, clasp cross bar 64 may immediately be seated in notches 35 and 36, but, if the safety catch is in its closed

position, as shown in Figure 7, the cross bar is forced against bevel 51a of the catch to open it. When clasp cross bar 64 is in the notches, swinging of lever 39 in a clockwise direction causes engagement of shoulder 41a of lever slot 47 by arm 50 of the pawl. Continued clockwise movement of lever 39 to its closed position (Figure 7), wherein detent 44 engages edge 23a, imparts clockwise movement to pawl arm 50, which bears against slot edge 54a of catch 52 to draw the catch to the left, as viewed in Figure 8. Thus finger piece 57 rides across bar 64 of clasp 19 to connect the bar, and accordingly the clasp to connector 15.

15 When lever 39 is swung counter-clockwise (Figure 7) to permit disconnection of the connector, its end 39a (Figure 3) which is preferably squared, rides into notches 31a and 38a (Figures 2 and 7) formed in ears 31 and 38, and 20 abuts against the ears to limit the opening movement of lever 39. The provision of these formations has the effect of strengthening the lever and guards against distortion thereof from the application of excessive opening movement.

25 Accordingly I have provided a bracelet end connector which accomplishes in a thoroughly practical and efficient manner the several objects set forth hereinabove.

As many possible embodiments may be made of the above invention and as many changes might be made in the embodiment above set forth, it is to be understood that all matter hereinbefore set forth, or shown in the accompanying drawing, is to be interpreted as illustrative and not 35 in a limiting sense.

I claim:

1. A bracelet end connecting device comprising, in combination, a link adapted to be secured to the end of a bracelet, said link including a 40 transverse cross bar having raised and depressed portions, a second link adapted to be connected to the other end of said bracelet and including a body portion, said body portion being formed to receive said cross bar, an operating member 45 associated with said body portion and formed to be threaded through said first-mentioned link to position said cross bar in connecting relationship with said body portion, and a safety catch positioned within said body portion for retaining said cross bar therein, said catch including a beveled portion positionable to be engaged by 50 said cross bar, said cross bar lying in the path of movement of said operating member whereby closing movement of said member forces the depressed portion of said cross bar against the beveled portion of said safety catch to move said 55 catch out of its cross bar retaining position.

2. A device of the nature described comprising, in combination, a body member having side walls 60 and a connecting web portion, said side walls having notches formed between the ends thereof adapted to receive a coupling or the like, a catch 65 slidably mounted in said body member adapted to slide from an open position spaced from said notches to a closed position wherein it blocks the entrance to said notches to hold the coupling 70 therein, the portion of said catch which blocks said notches having a beveled upper surface, and a second catch pivotally mounted on said body member and swingable from an open to a locking position where it overlies said first-mentioned catch and said notches, said second catch having a portion which engages said coupling to force it against said beveled surface when said first- 75 mentioned catch is in closed position to force

said first-mentioned catch into its open position to permit entrance of said coupling into said notches.

3. A device of the nature described comprising, in combination, a body member having side 5 walls and a connecting web portion, said side walls having notches formed between the ends thereof adapted to receive a coupling or the like, a catch 10 slidably mounted in said body member adapted to slide from an open position spaced from said notches to a closed position wherein it blocks the entrance to said notches to hold the coupling therein, the portion of said catch which blocks said notches having a beveled upper surface, a second catch pivotally mounted on said 15 body member and swingable from an open to a locking position where it overlies said first-mentioned catch and said notches, said second catch having a portion which engages said coupling to force it against said beveled surface when said first-mentioned catch is in closed position to force 20 said first-mentioned catch into its open position to permit entrance of said coupling into said notches, and a part operated by said second-mentioned catch and engageable with said first- 25 mentioned catch to force it into its closed position when the second catch is swung to its closed position.

4. A device of the nature described comprising, in combination, a hollow body member having 30 wall portions connected by a web portion, said wall portions having notches formed between the ends thereof adapted to receive a coupling or the like, a safety catch 35 slidably disposed in said body member and movable from an open position to a closed position wherein it overlies said coupling when the coupling is in said notches to retain the coupling therein, an operating member pivotally secured to said side walls and swingable from an open to a closed position overlying said safety catch and said coupling, and an element pivoted coaxially with 40 said operating member and engageable thereby upon closing movement thereof to force said safety catch into its closed position.

5. A device of the nature described comprising, in combination, a hollow body member having 45 wall portions connected by a web portion, said wall portions having notches formed between the ends thereof adapted to receive a coupling or the like, a safety catch 50 slidably disposed in said body member and movable from an open position to a closed position wherein it overlies said coupling when the coupling is in said notches to retain the coupling therein, an operating member pivotally secured to said side walls and swingable from an open to a closed position overlying said safety catch and said coupling, an element pivoted coaxially with 55 said operating member and engageable thereby upon closing movement thereof to force said safety catch into its closed position, and means forming a lost motion connection between said operating member and said element whereby closing movement of said operating member pivots said element against said safety 60 catch to close the catch, but opening movement of said operating member does not move said element or said catch.

6. A center catch for a wrist watch bracelet or the like, comprising, in combination, a body member formed to receive a link end, a slotted catch 65 movably associated with said body member and movable from an open to a closed position to retain said link end in related assembly with said body member, a movable lever operatively con- 70

- nected with said body member, and a part mov-
ably mounted in said body member and engage-
able by said lever upon operation thereof for
movement into the slot in said catch, whereby
5 movement of said lever moves said catch to its
closed position.
7. A center catch for a wrist watch bracelet
or the like, comprising, in combination, a body
member including a portion formed to receive
10 a link end, movable means for retaining said link
end in said body member, a part pivotally connected
to said body member and pivotable be-
tween open and closed positions with respect to
15 that portion of said body member formed to re-
ceive the link end, and a pawl in said body mem-
ber having a lost motion connection with said
part and operable thereby during closing pivoting
thereof to force said movable means into link
20 retaining position.
20. 8. A center catch for a wrist watch bracelet or
the like, comprising, in combination, a body mem-
ber including a portion formed to receive a link
end, movable means for retaining said link end in
25 said body member, a part pivotally connected to
said body member and pivotable between open
and closed positions with respect to that portion
of said body member formed to receive the link
end, a pawl in said body member associated with
30 said part and operable thereby during closing
pivoting thereof to force said movable means
into link retaining position, said pawl having a
lost motion connection with said part whereby
movement of said part to its open position leaves
35 said movable means in link retaining position,
and means associated with said movable means
accessible to manual engagement when said part
is in open position, whereby said movable means
may be moved from link retaining position.
9. A bracelet end connecting device, comprising,
40 in combination, a link adapted to be secured
to the end of a bracelet, said link having a trans-
verse coupling bar, a second link adapted to be
connected to the other end of the bracelet and
including a body portion, said body portion being
45 formed to receive said coupling, an operating
member associated with said body portion and
formed to be threaded through said first-men-
tioned link to position said coupling bar in con-
nected relationship with said body portion, and
50 a catch mounted in said body portion for move-
ment into and out of coupling bar retaining posi-
tion, said catch underlying said coupling bar when
the catch is in bar retaining position and the bar
is resting thereagainst and both the catch and
55 bar lying in the path of movement of said oper-
ating member which upon closing movement
thereof forces said bar against said catch to move
the catch out of its bar retaining position.
10. A center catch for a wrist watch bracelet
60 or the like, comprising, in combination, a channel-
shaped hollow body member having side walls
connected by a substantially flat web portion,
said wall portions having notches formed between
the ends thereof adjacent one end of said body
65 member and adapted to receive a coupling or the
like, the bottoms of said notches being spaced
above said web, a safety catch mounted in said
body member between said wall portions and hav-
ing an overhanging portion, said catch being mov-
70 able from an open position in which said over-
hanging portion is clear of said notches to a
closed position wherein said overhanging portion
overlies said coupling when the coupling is posi-
tioned in said notches, and a control member for
75 said catch movably mounted in said body member

independently of said catch between said wall
portions and in engagement with said catch, a
portion of said control member being located be-
tween said notches and above the bottoms thereof
when said catch is in said open position, where-
by said coupling engages said control member
upon insertion in said notches to effect movement
of said catch to its closed position.

11. A center catch for a wrist watch bracelet
or the like, comprising, in combination, a channel-
shaped hollow body member having side walls
connected by a substantially flat web portion, said
wall portions having notches formed between the
ends thereof adjacent one end of said body mem-
ber and adapted to receive a coupling or the like,
the bottoms of said notches being spaced above
said web, a safety catch mounted in said body
member between said wall portions and having
an overhanging portion, said catch being mov-
able from an open position in which said over-
hanging portion is clear of said notches to a
closed position wherein said overhanging portion
overlies said coupling when the coupling is posi-
tioned in said notches, a control member for said
catch movably mounted in said body member
independently of said catch between said wall
portions and in engagement with said catch, a
portion of said control member being located be-
tween said notches and above the bottoms thereof
when said catch is in said open position, whereby
said coupling engages said control member upon
insertion in said notches to effect movement of
said catch to its closed position, and a second
catch pivotally connected to said body member
and pivotable from an open position with respect
to said notches to a closed position with respect
thereto.

12. A center catch for a wrist watch bracelet or
the like, comprising, in combination, a channel-
shaped hollow body member having side walls
connected by a substantially flat web portion, said
wall portions having notches formed between the
ends thereof adjacent one end of said body mem-
ber and adapted to receive a coupling or the like,
the bottoms of said notches being spaced above
said web, a safety catch mounted in said body
member between said wall portions and having
an overhanging portion, said catch being movable
from an open position in which said overhanging
portion is clear of said notches to a closed posi-
tion wherein said overhanging portion overlies
said coupling when the coupling is positioned in
said notches, a control member for said catch
movably mounted in said body member independ-
ently of said catch between said wall portions
and in engagement with said catch, a portion of
said control member being located between said
notches and above the bottoms thereof when
said catch is in said open position, whereby said
coupling engages said control member upon in-
sertion in said notches to effect movement of said
catch to its closed position, and a second catch
pivotally connected to said body member and
pivotable from an open position with respect to
said notches to a closed position with respect
thereto, said second catch being operably dis-
associated with said safety catch at least during
opening operation, whereby said safety catch
remains closed upon said second catch being
opened.

13. A center catch for a wrist watch bracelet
or the like comprising, in combination, a channel-
shaped hollow body member having side walls
joined to the bottom of the body member, said
body member having a recess formed between the

ends thereof adjacent one end of said body member and adapted to receive a coupling or the like, the bottom of said recess being spaced above the bottom of said body member, a safety catch 5 mounted in said body member between said wall portions and having a coupling retaining portion, said catch being movable from an open position in which said coupling retaining portion is clear of said recess to a closed position wherein said 10 coupling retaining portion overlies said coupling when the coupling is positioned in said recess, and a control member for said catch movably mounted in said body member independently of said catch between said wall portions and in 15 engagement with said catch, a portion of said control member being located within said recess and above the bottom thereof when said catch is in said open position, whereby said coupling engages said control member upon insertion in 20 said recess to effect movement of said catch to its closed position.

14. A center catch for a wrist watch bracelet or the like comprising, in combination, a channel-shaped hollow body member having side walls 25 joined to the bottom of the body member, said body member having a recess formed between the ends thereof adjacent one end of said body member and adapted to receive a coupling or the like, a safety catch mounted for sliding movement 30 longitudinally within said body member between said wall portions, said catch having a coupling retaining portion and being movable from an open position to a closed position to overlie said coupling when the coupling is positioned in said 35 recess, a control member for said catch pivotally mounted between the side walls of said body mem-

ber and in operative engagement with said catch, a portion of said control member being located within said recess when said catch is in its open position, whereby the coupling engages said control member upon insertion in said recess to effect 5 movement of said catch to its closed position.

15. A device of the nature described, in combination, a body member having a recess adapted to receive a coupling or the like, a catch mounted in said body member and movable from a release 10 to a retaining position with respect to said coupling when in said recess, said catch including a lower portion lying within said body member near the bottom thereof, and a part movably mounted in said body member operatively associated 15 with said lower catch portion, said part being positioned for engagement by said coupling when it is placed within said recess to effect movement of said catch to its retaining position.

16. A device of the nature described, in combination, a body member having a recess adapted to receive a coupling or the like, a catch mounted in said body member and movable from a release to a retaining position with respect to said coupling when in said recess, said catch having a 25 portion which when the catch is in retaining position overlies said coupling when it is in said recess, said catch including another portion underlying said recess, and a part movably mounted in said body member engaging said 30 second-mentioned catch portion and adapted to effect movement of said catch to said retaining position when said part is engaged by said coupling.
